UNITED STATES PATENT OFFICE.

WILLIAM O. CARDIN, OF JOPLIN, MISSOURI, ASSIGNOR TO J. W. FREEMAN, OF JOPLIN, MISSOURI.

DEHYDRATOR.

1,423,188.

Specification of Letters Patent. Patented July 18, 1922.

Application filed November 23, 1920, Serial No. 426,060. Renewed December 21, 1921. Serial No. 523,881.

To all whom it may concern:

Be it known that I, WILLIAM O. CARDIN, a citizen of the United States, residing at Joplin, in the county of Jasper and State 5 of Missouri, have invented certain new and useful Improvements in Dehydrators, of which the following is a specification.

This invention relates to dehydrators, and it comprises certain novel combinations of 10 material containing means, and means for evenly distributing heat about the material being dried and means for controlling the passage of the heated air through the material containers.

15 An important object of the invention is to provide an apparatus of the above mentioned character in which a great variety of fruits, vegetables, meats, and the like, can be thoroughly dried and wherein only 20 water is removed from the material being dried so that it maintains its original color and taste.

Other objects and advantages of the invention will be apparent during the course 25 of the following description.

In the accompanying drawings forming a part of this specification and in which like numerals are employed to designate like parts throughout the same—

30 Figure 1 is a central vertical longitudinal sectional view of the device,

Figure 2 is a section taken on line 2—2 of Figure 1,

35 Figure 3 is a section taken on line 3—3 of Figure 1,

Figure 4 is a similar view taken in line 4—4 of Figure 1,

Figure 5 is a similar view taken on line 5—5 of Figure 1,

40 Figure 6 is a front elevation of a modified form of the device, parts being shown in section for the purpose of illustration, and,

45 Figure 7 is a section taken on line 7—7 of Figure 6.

In the drawings wherein for the purpose of illustration are shown preferred embodiments of my invention, the numeral 10 designates a heating unit as a whole, comprising a fire box 11, and ash pit 12. The heating unit 10 is mounted at one end of the device and serves as a support for the same. Secured to the lower face of the ash pit 12 is a plate 13, to which is secured a 50 pair of substantially hemispherical mem- bers 14, adapted for engagement within sockets 15 secured to the floor in any suitable manner. The members 14 and 15 serve as ball and socket joints, whereby the device may be tilted longitudinally. 60

The numeral 16 designates a heater casing, comprising a lower wall 17, end walls 18 and 19, and front and rear walls 20 and 21. The lower wall 17 of the heater casing is provided with an opening 22 to permit 65 the products of combustion from the fire to pass therethrough. Mounted above the lower wall 17 and spaced therefrom is a horizontal flue wall 23, providing a flue 24. It will be noted that the flue 24 is relatively 70 shallow but extends throughout the entire length and width of the heater casing so that the entire area of the lower face of the flue wall 23 is exposed to the action of the heat of the fire box. The end of the flue 75 24 opposite the heating unit is open and communicates with a flue pipe 25, the end of which is flared as at 26, at its point of connection with the flue 24. The flue 25 is provided with a damper 27 of the usual 80 type to regulate the fire in the fire box 11.

A pair of solid baffle plates 28 and 29 are mounted within the casing 17 horizontally thereof, forming passages 30 and 31, for the 85 passage of heated air. It will be noted that the baffle plates 28 and 29 are staggered, the plate 28 having one end in connection with the wall 18 of the casing 16, and its opposite end spaced from the wall 19, while the baffle plate 29 has one end connected to the wall 90 19 of the casing 16, and its opposite end spaced from the wall 18. The passage 30 has communication with the atmosphere through opening 32 in the end wall 18 of the casing 16. The baffles 28 and 29 serve to retard the movement of the heated air, for a 95 purpose to be described. A second pair of baffle plates 33 and 34 are also mounted within the casing 16, these baffle plates being also spaced from each other, and from the baffle 100 plate 29. As shown in Figure 5, the baffle plate 33 is provided in each corner with relatively large openings 35, and substantially centrally of its length with relatively small openings 36, for the passage and distribution of heated air. If desired, the corners of the baffle plate 33 may be reenforced, as at 105 37, and the longitudinal center of the plate reenforced, as at 38. The baffle plate 34 is provided around the outer portion thereof 110

with small, spaced openings 39 to further distribute the heated air. It will be noted that the center portion of the plate 34 is solid. As shown in Figures 1 and 2, the upper end of the casing 16 is open, the walls 20 and 21 being provided with narrow, inwardly extending flanges 40, for a purpose to be described.

A drier casing 41 is mounted above the 10 casing 16, and it comprises a substantially semi-circular upper wall 42, and vertical front and rear walls 43 and 44. The drier casing 41 is also provided with vertical end walls 45 and 46. The end walls 45 and 46 have bearings 47 and 48 mounted thereon to 15 receive the central longitudinal shaft 49.

A rotatable material container 50, preferably of open mesh wire, is mounted within the casing 41, the container 50 being provided at its ends with reenforcing bands 51, connected by arms 52 with the shaft 49. The arms 52 may be secured to the shaft 49 in any suitable manner, such as by collars 53 and set screws 54. The shaft 49 is connected 20 with the container 50 at intervals throughout its length by collars 55 and spiders 56. One end of the shaft 49 is provided with a gear 57 adapted to be driven from any suitable source of power. The container 50 is 25 provided substantially centrally thereof with spaced bearing bands 58, adapted to contact rollers 59 carried by bearings 60, secured to the plate 34. The rollers 59 serve to support the central portion of the container 50 to relieve the central portion of the shaft of strain when the device is in operation, and the container filled with the material being dried.

The end wall 46 of the casing 41 is provided with a hopper 61 through which the 40 material to be dried is fed to the cylinder. The hopper 61 is preferably provided with a hinged cover 62. The opposite end 45 of the casing 41 is apertured, as at 63, for 45 the egress of the material within the cylinder after it has been dried. The aperture 63 communicates with a discharge chute 64 and the aperture 63 is closed during the 50 operation of the machine by a gate or slide 65, slidable within openings 66 in the walls of the chute 64.

The upper portion of the casing 41 is provided with branch flues 67 through which the heated air passes from the casing 41. 55 The flow of heated air is governed by suitable dampers 68. The heated air passes from the branch flues 67 to a collector flue 69 and main flue 70, which carries the air to the heater flue 25.

60 An internally threaded block 71 is attached to the under side of the wall 17 at the end opposite the heater and a similar block 72 is attached to the floor, the blocks 71 and 72 being normally spaced apart when 65 the device is in the horizontal or normal

position. The openings in the blocks 71 and 72 are oppositely screw-threaded to receive the oppositely screw-threaded nuts on a jack screw 73, adapted to be rotated through the medium of a handle or wheel 74. 70

In Figures 6 and 7, I have illustrated a modified form of the invention, wherein the heater element 10 is adapted to rest directly upon the floor, the opposite end of the device being supported upon legs 75. The 75 heater casing 16 is provided with an arrangement of flue, baffle plates, and air passages similar to that shown in the preferred embodiment of the invention.

In this form of the invention, I prefer to 80 provide separable container units 76, the fronts, tops and bottoms of which are open, having solid end and back walls 77 and 78. The end walls 77 of the casings 76 are provided with supports 79 adapted to support 85 trays 80. The trays 80 are preferably formed of open mesh wire, the outer edges of which are attached to solid frames 81.

The fronts of the units 76 are adapted to be closed while the device is in operation 90 by doors 82, preferably provided with a packing 83 of felt or the like. The center of the doors 82 are apertured to receive threaded bars 83, connected to the outer face of the door with a rotatable wheel 84. The 95 inner or screw-threaded ends of the bars 83 are adapted to be received in screw-threaded openings of transverse bars 85, extending between the ends of the units 76. It will be apparent that when the inner ends 100 of the bars 83 are introduced into the openings in the bars 85 and the wheels 84 rotated, the doors 82 may be clamped tightly against the fronts of the casings to prevent leakage of the heated air. 101

The upper ends of the units 76 are adapted to be closed by an inverted V-shaped top 86 provided with closed ends 87. The heated air within the casings 76 is adapted to pass out through branch flues 88, and the 11 top 86 is provided with baffle plates 89 arranged directly below the flues to prevent the heated air from being drawn directly into the flues. If desired, the top 86 may be provided with thermometers 90, so that 11 the heat within the casings may be determined at any time.

The operation of the preferred form of my invention is as follows:

The fire within the fire box 71 is adapted 12 to heat the wall 23 throughout its entire area, the products of combustion passing out through the flue 25. Air is admitted through the opening 32 and passes slowly along the passage 30 in contact with the 12 wall 23, and becomes heated to a high temperature. The arrangement of the baffle plates 28 and 29 serve to retard the passage 13 of the air so that it is maintained in contact with the plate 23 throughout a longer 13

period of time. The plate 33 serves to initially distribute the air after it has been heated, while the plate 34 subsequently more thoroughly distributes the air, whereby the heat may be thoroughly distributed through the casing 41 so that the material therein is subjected to an even heat throughout the container 50.

The material is fed to the container 50 through the hopper 61, the device being in the position shown in Figure 1. After the material within the container 50 has been suitably dried, the slide 65 is opened, and the wheel 74 rotated, elevating the end of the casing so that the dried material moves to the opposite end of the container and is discharged through the aperture 63 and chute 64.

In the modified form of the invention, the material is placed upon the trays 80 and the trays inserted within the casings 76, as shown. The door 82 is then closed in the manner described, until the material has been suitably dried, when the trays may be withdrawn.

It is to be understood that the forms of my invention herewith shown and described are to be taken as preferred examples of the same, and that various changes in the shape, size, and arrangement of parts may be resorted to without departing from the spirit of the invention or the scope of the subjoined claims.

Having thus described my invention, I claim:

1. In a device of the character described, a heating unit, a heater casing, said heater casing comprising a flue communicating with said heating unit, a plurality of staggered baffle plates, a plate mounted above said baffle plates and provided with relatively large openings, and a distributing plate mounted above said last named plate and provided with relatively small openings, said heater casing being provided with an air intake opening, a casing mounted above and communicating with said heater casing, and means carried within said last named casing for supporting the material to be dried.

2. In a device of the character described, a heating unit, a heater casing, said heater casing comprising a flue communicating with said heating unit, a plurality of baffle plates, each of said baffle plates having an end secured to opposite ends of said heater casing and the opposite ends spaced from the opposite ends of said heater casing, a plate mounted above said baffle plates and provided adjacent its corners with relatively large openings, and a distributing plate mounted above said last named plate and provided adjacent its edges with relatively small openings, the central portion of said distributing plate being solid, said heater

casing being provided with an air inlet opening arranged below the lowermost baffle plate, a casing mounted above and communicating with said heater casing, and means carried within said last named casing for supporting the material to be dried.

3. In a device of the character described, a heating unit, a heater casing, said heater casing comprising a flue communicating with said heating unit, a plurality of staggered baffle plates, a plate mounted above said baffle plates and provided with relatively large openings, and a distributing plate mounted above said last named plate and provided with relatively small openings, said heater casing being provided with an air intake opening, a casing mounted above and communicating with said heater casing, and a rotatable perforate material supporting member mounted within said last named casing.

4. In a device of the character described, a heating unit, a heater casing, said heater casing comprising a flue communicating with said heating unit, a plurality of staggered baffle plates, a plate mounted above said baffle plates and provided with relatively large openings, and a distributing plate mounted above said last named plate and provided with relatively small openings, said heater casing being provided with an air intake opening arranged below the lowermost baffle plate, a casing mounted above and communicating with said heater casing, a rotatable perforate material supporting member mounted within said last named casing, and means for tilting said heater casing.

5. In a device of the character described, a heating unit, a heater casing, said heater casing comprising a flue communicating with said heating unit, a plurality of staggered baffle plates, a plate mounted above said baffle plates and provided with relatively large openings and a distributing plate mounted above said last named plate and provided with relatively small openings, said heater casing being provided with an air intake opening arranged below the lowermost baffle plate, a casing mounted above and communicating with said heater casing, a rotatable perforate material supporting member mounted within said last named casing, a discharge chute mounted at one end of said last named casing, a door mounted adjacent said discharge chute, and means for tilting said heater casing.

6. In a device of the character described, a heating unit, a heater casing, said heater casing comprising a flue communicating with said heating unit, a plurality of staggered baffle plates, a plate mounted above said baffle plates and provided with relatively large openings, and a distributing plate mounted above said last named plate and provided

4
with relatively small openings, said heater casing being provided with an air intake opening, a casing mounted above and communicating with said heater casing, a rotatable shaft carried by said last named casing, a cylindrical perforate material supporting member mounted upon said shaft, and means carried by said distributing plate for supporting said material supporting member between the ends thereof.

5 7. In a device of the character described, a heating unit, a heater casing, said heater casing comprising a flue communicating with said heating unit, a plurality of staggered 10 baffle plates, a plate mounted above said baffle plates and provided with relatively large openings, and a distributing plate

mounted above said last named plate and provided with relatively small openings, said heater casing being provided with an 20 air intake opening, a casing mounted above and communicating with said heater casing, a rotatable shaft carried by said last named casing, a cylindrical perforate material supporting member mounted upon said shaft, 25 a bearing band secured to the outer face of said material supporting member, a pair of rollers mounted upon said distributing plate and adapted to contact said bearing band, means for governing the discharge of material from said material supporting member, and means for tilting said heater casing.

15 In testimony whereof I affix my signature.
WILLIAM O. CARDIN.
